(57) **CLAIM**

I claim the ornamental design for a bolster cargo cover, as shown and described.

DESCRIPTION

FIG. 1 is a top right perspective view of a bolster cargo cover;

FIG. 2 is a top view of the bolster cargo cover of FIG. 1;

FIG. 3 is a bottom view of the bolster cargo cover of FIG. 1;

FIG. 4 is a left side view of the bolster cargo cover of FIG. 1;

FIG. 5 is a right side view of the bolster cargo cover of FIG. 1;

FIG. 6 is a front view of the bolster cargo cover of FIG. 1; and,

FIG. 7 is a back view of the bolster cargo cover of FIG. 1. The breaks in the drawing figures show no specific length.
